UNITED STATES PATENT OFFICE.

JAMES C. MOORE, OF SMYRNA, NEW YORK.

ELECTRICIAN'S JOIST-BORING TOOL.

1,391,844.

Specification of Letters Patent. Patented Sept. 27, 1921.

Application filed January 26, 1920. Serial No. 354,312.

To all whom it may concern:

Be it known that I, JAMES CLARENCE MOORE, a citizen of the United States, and a resident of Smyrna, in the county of Chenango and State of New York, have invented a new and Improved Electrician's Joist-Boring Tool, of which the following is a full, clear, and exact description.

My invention relates to a certain novel and useful improvement in boring machines, and specifically appertains to a mechanism of the type referred to designed especially for use in boring holes in the joists of ceilings or floors for the passage of concealed full, clear, and exact description.

An object of the invention is to provide an improved boring tool compact in a small area of space which tradesmen easily can carry about in their tool bag without the inconveniences caused by the larger boring machines.

A further object of the invention is to materially reduce the length of the machine from front to rear in order that it may be conveniently introduced between beams, joists and the like, particularly when they are closely arranged.

Still a further object of the invention is the combination and arrangement of the gears; gear shafts and gear bearings in a one piece gear casing and its cover, within a small area of space, so as to provide simplicity and high speed, the latter which is essential in performing quick work.

With the above recited objects and others of similar nature in view, my invention consists in the combination and arrangement of parts, as will be hereinafter more fully described, shown in the accompanying drawings, and particularly pointed out in the appended claim, it being understood that changes in the form, proportion, size and minor details may be made within the scope of the claim without departing from the spirit or sacrificing any of the advantages of the invention.

Reference is to be had to the accompanying drawings, forming a part of this specification, in which similar characters of reference indicate corresponding parts in all the figures.

Figure 1 is a vertical sectional view of my machine embodying my improvements, said view also illustrating the manner of applying the same when used.

Fig. 2 is an end elevation thereof.

Fig. 3 is an elevation view of the steady-
ing rod bracket showing the side of said
bracket which is fastened under the clamp-
ing nut of the steadyng rod.

60

Fig. 4 is an elevation view of the steady-
ing rod bracket showing the side of said
bracket which is at right angles to Fig. 3
and receives the steadyng rod.

Fig. 5 is a detail view of one of the grips used in the construction of the bit chuck.

Referring now to the accompanying drawing in detail, the turning handle 30 is adapted to turn or revolve freely on its connecting bolt 31 the said bolt fixed solidly to driving gear A. The driving gear A is loosely rotatable on a stationary shaft 1 secured by washer 3 and locknut 4 and meshes with and imparts motion to gear B, the said gears being mounted outside of the casing 75 cover 29 and adjacent to the front side thereof. Gear B is fastened by a groove key to rotating shaft 9, the said shaft extending through casing cover 29 rotating in bearings 2 and carrying gear C the said gear being 80 solidly fastened to shaft 9 by a groove key. Gear C meshes with and imparts motion to gear D within the casing, the latter screws onto rotating bit chuck shaft 17. A pin is driven through gear D and shaft 17 to prevent loosening. An end portion of shaft 17 that turns or revolves in projecting bearing 19 in the casing cover is machined or turned down by lathe until the threads are removed making that end of shaft smaller at 18. The 90 revolving shaft 17 extends through the back portion of the casing 28 just sufficient to manipulate the bit chuck gripping bit 25.

The bit chuck is constructed with a hollow cylinder 22 threaded inside at one end with 95 nut 21 screwed into said end of cylinder and fastened by pin 23.

Fig. 5 shows detail view of one of the bit chuck jaws. The shank of the bit rests in grooves 26 and 27.

100

Jaws 24 are adjusted by revolving cylinder 22 around on shaft 17, by threads 20.

The steadyng handles 8 consist of two L-shaped rods 7 threaded at the ends which extend through the projecting portions (15) 105 of casing and cover and are fastened by the clamping nuts 5 and 6. The unthreaded ends of rods 7 touch each other in the center of hollow steadyng hand-grip 8.

Figs. 3 and 4 are elevations of the two 110 sides of steadyng rod bracket. Under the two lower clamping nuts 5 are fastened pro-

jecting part 14 of the said bracket, while projecting pieces 11, 12, 13 merely press against the casing. The bracket supports steadyng rod 16, the said rod resting in holes 10. The lower portion of case and cover are connected by bolt 32.

From the above description, taken in connection with the drawings, the manner of employing my machine will be readily apparent.

The horizontal rod 16 carrying the machine is placed transversely of the flooring Z resting on joists X and Y to be operated upon, pivoting the machine up or down on rod 16 until the bit 25 is in contact with the spot where the joists are to be bored.

The turning handle 30 is then actuated by the operator, and a rotary motion is imparted to the bit through gear A, gear B, shaft 9, gear C, gear D, and shaft 17, connected to the bit 25.

The hole or boring made with this machine will extend in a direct line transversely through the board or joist and it is not necessary, as is commonly the case, to bore the hole at an inclination or angle through such joists. After the bits have passed through the wood and the boring is made, with the left hand still on the left hand steadyng hand-grip 8, remove the right hand from the turning handle 30 and grasping the right hand steadyng hand-grip 8, the operator now pulls toward him with both hands, and the said movement will 35 remove the bit from the joist and the opera-

tion of boring new holes may be proceeded with.

It will be observed that I have provided an exceedingly simple machine and one which possesses many advantages over similar mechanisms of the character now in general use, and while I have herein shown and described one particular embodiment of the invention, it will of course be understood that I do not limit myself to all the precise details thereof, as there may be modifications in certain respects without departing from the essential features of the invention or sacrificing any advantages thereof.

Having thus described my invention I claim as new and desire to secure by Letters Patent—

A portable joist-boring tool, comprising a frame or casing supporting gearing and having a bit chuck projecting from one face, a pair of bracket plates on opposite edges of said frame having alined perforations to receive a rod transversely to said bit projecting beyond the frame to rockingly support the same on spaced supports and handle grips projecting from the opposite face at opposite edges.

In testimony whereof I have signed my name to this specification in the presence of two subscribing witnesses.

JAMES C. MOORE.
